UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

TALKING-MACHINE.

1,321,177.

Specification of Letters Patent. Patented Nov. 11, 1919.

Application filed April 15, 1918. Serial No. 91,340.

To all whom it may concern:

Be it known that I, JOSEPH WOLFF, a subject of the King of Great Britain and Ireland, residing in the borough of Brooklyn, 5 county of Kings, and State of New York, have invented a certain new and useful Improvement in Talking-Machines, of which the following is a specification.

My invention relates to talking machines, 10 and more particularly to the recording and reproducing devices used therein, and has for its object to simplify and cheapen the construction thereof.

A further object is to so design the apparatus that the initial tension of the diaphragm may be adjusted within narrow 15 limits and with absolute certainty.

These and further objects will more fully appear in the following specification and accompanying drawings, considered together 20 or separately.

I have illustrated my invention in the accompanying drawings, in which,—

Figure 1 is a front elevation on a larger 25 scale;

Fig. 2 is a side elevation;

Fig. 3 is a section on the line 3—3 of Fig. 1; and

Fig. 4 is a section on the line 4—4 of 30 Fig. 1.

In all of the above views, like parts are designated by similar reference characters.

In the drawings, 1 designates the body of a reproducer. The body is preferably made 35 cylindrical, and the front face is recessed as at 2. The rear face of the body is provided with an annular flange 3, which forms a cylindrical pocket 4.

A diaphragm 5 is supported in the recess 40 2, between annular cushions 6, 6. The recess 2 and pocket 4 are in communication by means of an opening 7. The cushions and diaphragm are secured in position by means of a flat annulus 8, which is attached to the body 1 by means of screws.

A stylus carrier 9 is provided with an arm 10, at the extremity of which is a disk 11. A screw 12 passes through the diaphragm at its center, and enters the disk 11, thereby firmly 50 and removably securing the diaphragm and stylus carrier together. The body of the stylus carrier is provided with wings 13, 13, which project in opposite directions in the plane of and parallel with the body portion 55 and transversely of the axis thereof, and the

extremities 14 and 15 of the wings are extended or projected in opposite directions and outside of or beyond the pivot screws.

Extending from one side of the body 1 is a block 16, through which two conical 60 pointed pivot screws 17, 17 extend. The conical ends of the screws engage conical recesses 18, 18, formed in and located at about the longitudinal center of the wings 14, 15, and beyond the oppositely extended portions 65 thereof, and which recesses or bearings are somewhat larger than the points of the screws, to allow movement of the stylus in any direction relatively to the screws. The opposite ends of the screws project from the 70 opposite side of the block 16 and are provided with suitable nicks to receive a screwdriver whereby the screws may be adjusted.

Screws 19, 19 are threaded in the block 16, and extend through the oppositely extended 75 portions or extremities 14 and 15 of the wings 13, and helical springs 20 are interposed between the heads of the screws and the wing through which the screw passes.

It will be seen that by this arrangement 80 the screws 19 are located beyond or out of alignment with the pivot screws and are positioned on opposite sides of a straight line drawn through the centers of the pointed pivot screws 17. By this means, when the 85 extremity 14 of a wing 13 is depressed by setting up one screw 19, the stylus carrier will be inclined to flex the diaphragm in one direction, and when the extremity 15 is depressed by setting up on the other screw 19, 90 the diaphragm will be flexed in the other direction. By this means the diaphragm may be given the exact initial tension desired.

The helical springs 20, being located on 95 opposite sides of the rocking points of the stylus carrier, will act as cushions when the carrier is tilted in either direction by sound waves, in a recorder, or by the engagement of the stylus with a record groove.

Seated within the pocket 4 is a coupling 100 21 for attachment to a tone-arm (not shown). The coupling is provided with a circumferential rib 22 which is seated between cushions 23, 23, held within the pocket by a ring 24.

While I have shown my invention as applied to a talking machine reproducer, I desire to have it understood that the same may be employed in a recorder, and in the following claims I employ the term "repro- 110

ducer" as meaning either a recorder or reproducer.

The operation of my improved device will be obvious from the above description.

- 5 In accordance with the provisions of the patent statute, I have described the principle of my invention, together with the apparatus, which I now consider to represent the best embodiment thereof, but I desire to
10 have it understood that the apparatus shown is merely illustrative, and that the invention can be carried out in other ways without departing from the spirit of the invention.
- 15 Having now described my invention, what I claim as new and desire to secure by Letters Patent of the United States, is as follows:
1. A reproducer, comprising a cylindrical body, a diaphragm mounted therein, a block fixed to and projecting from the body, conical pointed pivot screws fitted in said block and projecting from opposite sides thereof, a stylus carrier fixed to said diaphragm and
20 extending over and beyond said block and provided with laterally and oppositely extending wings overlying said block in the plane of and parallel with and transversely of the axis of the body portion and engaging
25 the conical points of said pivot screws, the ends of said wings projecting beyond said pivot screws and provided with oppositely extended portions projecting upon opposite
- 30

sides of the line of said pivot screws, screws fixed in said block and passing through 35 openings in the oppositely extended end portions of said wings, and springs fitted upon said screws between the heads thereof and said wings.

2. A reproducer, comprising a cylindrical body, a diaphragm mounted therein, a block fixed to and projecting from the body, conical pointed pivot screws fitted in said block and projecting from opposite sides thereof, a stylus carrier fixed to said diaphragm and 45 extending over and beyond said block and provided with laterally and oppositely extending wings overlying said block in the plane of and parallel with and transversely of the axis of the body portion and engaging 50 the conical points of said pivot screws and provided with oppositely extended portions projecting upon opposite sides of the line of said pivot screws and located outside of the limits of said screws, screws fixed in 55 said block and passing through openings in the oppositely extended end portions of said wings, and springs fitted upon said screws between the heads thereof and said wings.

This specification signed and witnessed
this 29 day of March, 1916.

JOSEPH WOLFF.
